[57] ABSTRACT

A plate rubbing member for a lithographic plate developing machine which includes a core of tubular conformation. A plurality of spaced rods are secured to the outer periphery of the core and extend longitudinally thereof. The exterior surface of each rod is provided with a friction surface. A tubular member of yieldable absorbent material is sleeved over the core and the friction surfaces of the rods grip the inner periphery of the tubular member in a manner to prevent rotary and longitudinal movement of the tubular member relative to the core upon rotation and oscillation of the rubbing member. Disks on the rubbing member engageable with the terminals of the tubular member positively preclude the absorbent material from sliding back and forth on the core during oscillating movement of the rubbing member.

**PLATE RUBBING MEMBER FOR LITHOGRAPHIC
PLATE DEVELOPING MACHINE**

BACKGROUND AND OBJECTS

In the developing machine forming the subject matter of my pending application Ser. No. 814,516, filed Apr. 9, 1969, now U.S. Pat. No. 3,534,882, a salient feature of this machine is a plate rubbing member which "works up" an image on an exposed lithographic plate. For performing this function, the rubbing member includes a cylindrical sponge which is rotated about its longitudinal axis which lies parallel to the surface of the plate to be developed. The lower portion of the rotating sponge passes through a pan of developing solution to impregnate the sponge with the solution. The periphery of the sponge engages the exposed face of the lithographic plate to "work up" the image and nonimage areas of the plate.

Since an absorbent and pliable material is used for contact with the plate, this material must be mounted on a solid core member in order to lend the desired stability to the roller operation. Also, the material must be readily removable from the core in order to permit replacement after a period of use.

It is an object of this invention to provide a plate rubbing member including a core on which is sleeved a yieldable and absorbent material, the core being so constructed to prevent relative rotation and/or longitudinal movement of the absorbent material with respect to the core.

Another object is to provide a plate rubbing member of the character described, wherein the core is tubular and the outer periphery thereof is provided with a series of fixed, rodlike protuberances extending longitudinally of the core for engaging and gripping the inner periphery of the absorbent material, the protuberances being provided with friction surfaces throughout their lengths to positively preclude longitudinal movement of the absorbent material with respect to the core.

A further object is to provide a developing roller which may be economically manufactured and which applies a uniform rubbing action to each plate being developed.

Other objects will be manifest from the following description of the presently preferred form of the present invention taken in conjunction with the appended drawing.

DESCRIPTION OF FIGURES OF DRAWING

FIG. 1 is an elevational view of the plate rubbing member of the present invention; 45

FIG. 2 is a perspective view of the plate rubbing member of the present invention, portions thereof being broken away to disclose details;

FIG. 3 is an enlarged end elevational view of the same;

FIG. 4 is a sectional view taken along the line 4—4 of FIG. 2, looking in the direction of the arrows, and

FIG. 5 is a fragmentary, enlarged longitudinal sectional view of the core forming a part of the present invention.

DETAILED DESCRIPTION OF THE INVENTION

The plate rubbing member of the present invention comprises a core generally designated 20 and a plate engaging portion designated 22.

Core 20 includes a tubular member 24 made of metal or any other suitable rigid material. Adjacent one terminal, the thickness of tubular member 24 is reduced at 26 to provide a shoulder or abutment 28. A locating slot 30 extends inwardly from the extreme terminal of one end of the tubular member 65 to abutment 28 for rotatably mounting the roller on a developing machine of the character described in my pending application Ser. No. 814,566.

It is a salient feature of the present invention to provide a plurality of rodlike protuberances on the outer periphery of tubular member 24, the protuberances preferably comprising a series of rods 32 which are welded or secured in any other suitable manner to member 24. If desired, the protuberances may, of course, be formed integrally with tubular member 24 to provide a unitary core structure.

In accordance with the present invention, rods 32 are threaded at 34 to provide a friction surface for purposes which will be hereinafter more fully set out.

Plate rubbing member 22 includes an absorbent, yieldable cylindrical member 36, made of synthetic sponge or other suitable material which may be sleeved over core 20. As shown to advantage in FIG. 4, rods 32 along the outer periphery of tubular member 24 engage the inner periphery of member 36 in a manner to prevent relative rotational movement of member 36 with respect to core 20.

Threads 34 of rods 32 also engage the inner periphery of member 36 in a manner to prevent longitudinal movement of member 22 with respect to core 20.

In order to positively preclude any relative longitudinal movement of member 22 with respect to core 20, end disks 38 are affixed by suitable means 40 to core 20, the disks being in contiguous engagement with the terminals of member 36 to confine the latter therebetween.

Although six rods are illustrated as applied to tubular member 24, any desired number for carrying out the purposes of the present invention may be employed. Optimum results have been obtained with this number of rods applied to a 2 1/4 inch diameter tube, on which a cylindrical sponge member of 5 1/2 inches in diameter has been sleeved.

With the device of the present invention, accidental displacement of the yieldable cylindrical member with respect to the core is obviated but, at the same time, replacement of the cylindrical member is readily effected.

What I claim is:

1. A plate rubbing member for a lithographic plate developing machine, including:

- a. a core comprising a tubular member,
- b. a plurality of uniformly spaced rods secured to the outer periphery of said tubular member,
- c. said rods extending longitudinally of said tubular member,
- d. the surface of said rods being threaded to provide a friction surface,
- e. a cylindrical member of yieldable, absorbent material in sleeved engagement with said core,
- f. said cylindrical member being engaged by said rods,
- g. whereby upon rotation of longitudinal oscillation of the rubbing member, said rods prevent relative rotation of the core with respect to the cylindrical member, and the threaded surface of the rods prevents relative longitudinal movement of said core with respect to the cylindrical member.

2. The plate rubbing member of claim 1, with the addition of:

- a. retaining disks carried by said core and engageable with the terminals of said cylindrical member.

3. A plate rubbing member for a lithographic plate developing machine including:

- a. a core comprising a tubular member,
- b. a yieldable cylindrical member in sleeved engagement with said core,
- c. a first means carried by said tubular member and frictionally engaged with said yieldable member, for preventing relative rotational movement between said tubular and cylindrical members,
- d. a second means carried by said first means and frictionally engaged with said yieldable cylindrical member for preventing relative longitudinal movement between said tubular and cylindrical members, and
- e. said second means comprising a threadlike surface extending transversely of said first means, and substantially coextensive with the length thereof.

4. The plate rubbing member of claim 3 wherein:

- a. said first means comprises a plurality of rods secured to the outer periphery of said tubular member.

5. The plate rubbing member of claim 3 with the addition of:

- a. retaining discs carried by said core and engageable with the terminals of said yieldable cylindrical member.

6. The plate rubbing member of claim 3, wherein:
a. said yieldable cylindrical member is made of a material
having the absorbent qualities of sponge.
